CLAIM

The ornamental design of a geometrical column unit as shown and described.

DESCRIPTION

FIG. 1 is a perspective view of a geometrical column unit of a new, original, and ornamental design;

FIG. 2 is a front and back side view of a geometrical column unit being a mirror image thereof;

FIG. 3 is a right and left side view of a geometrical column unit being a mirror image thereof; and,

FIG. 4 is a top and bottom view of a geometrical column unit being a mirror image thereof.

The geometrical column unit is intended to be stacked as a repeatable unit.
